UNITED STATES PATENT OFFICE.

GILBERT L. HUFF, OF HOLDENVILLE, OKLAHOMA.

COIN-CONTROLLED MECHANISM.

1,344,086.

Specification of Letters Patent. Patented June 22, 1920.

Application filed May 6, 1918. Serial No. 232,859.

To all whom it may concern:

Be it known that I, GILBERT L. HUFF, a citizen of the United States of America, residing at the city of Holdenville, county of Hughes, State of Oklahoma, have invented a certain new and useful Coin-Controlled Mechanism, of which the following is such a full, clear, and exact description as will enable any one skilled in the art to which it appertains to make and use the same, reference being had to the accompanying drawings, forming part of this specification.

My invention relates to a coin controlled mechanism and more particularly to one in which the mechanism not only controls a suitable vending device, but at the same time registers the amount of the various coins upon a single register.

The object of my invention is to provide a coin controlled mechanism of the class above referred to which will be simple in construction and reliable in operation and not liable to get out of order.

In the accompanying drawings which illustrate one form of coin controlled mechanism made in accordance with my invention, Figure 1 is a top plan view, Fig. 2 is a section taken on the line 2—2 of Fig. 1. Fig. 3 is a front view. Fig. 4 is a section 30 taken on the line 4—4 of Fig. 1. Fig. 5 is a section taken on the line 5—5 of Fig. 3. Fig. 6 is a development of a portion of the toothed wheel carried by the operating shaft, and Fig. 7 is an enlarged view, showing a detail of construction.

The frame of the device is composed of a pair of end plates 10 and 11, secured together by means of pillars 12. Journaled in the end plates 10 and 11 is an operating shaft 13 which has secured to one end a hand wheel 14 by means of which it may be operated, and at the other end is provided with an extension 15 which may be used to operate any suitable vending device, such as that shown in my prior application #214,533 of January 30, 1918. Secured to the operating shaft 13 is a wheel 16 which for convenience in manufacture is preferably built up of a number of disks of sheet metal, the number of disks corresponding to the number of different coins which the device is intended to handle. In the present instance, the wheel is composed of three disks of metal as the machine is intended to handle dimes, pennies, and nickles. One of the sheets of metal forming a wheel 16 is pro-

vided with a set of ten teeth 17, another with a single tooth 18, and another with five teeth 19, which teeth are adapted to be brought into operating connection with the registering device as will be hereafter described. 20 is a registering device which may be of any suitable kind. In the drawings, I have shown the well known form of Veeder register. The register 20 is provided with a gear wheel 21 the thickness of which is equal to that of the wheel 16 upon the operating shaft 13. In order to connect the teeth on the wheel 16 with the wheel 21, I provide idler wheel 22 which is loosely mounted in an annular groove 23 in a sleeve 24 sliding upon a shaft 25. The sleeve 24 is carried by a lever 26 in the general form of a bell crank. This lever 26 is provided at the end opposite the sleeve 24 with an opening 27 adapted to slide on a guide rod 28. The lever 26 is normally forced toward the plate 10 by means of a coil spring 29 surrounding the rod 25. The lever 26 is provided with a projection 30 adapted to enter a cam slot 31 in the side of the wheel 16, said cam slot 31 being provided at one end with a beveled face 32 as shown in Fig. 2 of the drawings. The projection 30 normally rests against the cam 32 of wheel 16, holding arm 26 and hence pinion 22 which it carries in the position shown in Fig. 1 against the pressure of spring 29, until on the initial movement of the wheel 16 said spring forces it through the cam slot 31 of the wheel shifting pinion 22 to engage with the selected segment of wheel 16 as will be later explained. The lever 26 is also provided with an arm 33 provided on its end with a pair of bearing faces 34 and 35 respectively, as best shown in Fig. 7 of the drawings.

36 is a plate separated from the end plate 10 by means of a pair of spacing blocks 37 and 38, best shown in Fig. 5 of the drawings. This plate 36 has secured in it one end of the shaft 25 and also has secured to it one end of a plate 39, the other of which is secured to the end plate 11, and supports the register 20 heretofore referred to. Secured to the spacing block 37 is a spring 40 which forms one of the stops for supporting the coin in the machine, the other consisting of a fixed pin 41 secured in the plates 10 and 36. The spacing block 38 is provided with an inclined surface 42 against which the coin is adapted to strike as it is discharged be-

tween the stops 40 and 41, as will be herein-after more fully described.

Pivoted between the plates 10 and 36 on a trunnion 43 is a bell crank lever 44 one end 5 45 of which is normally in the path of a finger 46 carried on the wheel 16. The other end 47 of the lever is adapted to be projected into the path of the arm 33 on the lever 26. The upper end of the bell crank 10 lever 44 is provided with a face 48 which is preferably curved and which terminates in a shoulder 49 adapted to bear against a coin 50 when the same is supported between the stops 40 and 41.

15 The operation of my device is as follows: The parts being in position as shown in Fig. 4 of the drawings, the handle wheel 14 cannot be turned because the stop 46 on the wheel 16 bears against the end 45 of the 20 bell crank lever 44. If, however, a coin is dropped between plates 10 and 36 the pressure of the coin against the face 48 of the bell crank lever 44 will force the upper end 47 of said lever forward and consequently 25 move the arm 45 out of the path of the stop 46, which path is indicated by the dotted line A, Fig. 5 of the drawings. The hand wheel 14 can now be operated to rotate the shaft 13 and consequently to actuate the 30 vending mechanism to which the extension 15 is connected. In case a dime is dropped into the machine, the end 47 of the lever 44 will not be moved sufficiently to come between the end of the lever 33 and the plate 35 10 and consequently when the wheel 16 is moved to allow the projection 30 to drop into the cam slot 31, the idler wheel 22 will be moved by the spring 29 until the face 34 of the arm 33 strikes against the end plate 40 10 and consequently the idler wheel 22 will be moved into the path of the teeth 17 so that when the shaft is rotating the register 20 will be operated to indicate ten. In case a penny is dropped into the machine the end 45 47 will be moved over sufficiently to come between the plate 10 and the bearing face 35 of the arm 33 so that the wheel 22 will be moved over only sufficiently to engage with the tooth 18 and consequently to register one. If a five cent piece is dropped in the machine, the end 47 will be moved over to its extreme position as shown in Fig. 5 50 of the drawings so that said end will come between the plate 10 and the bearing face 55 34 and consequently the idler 22 will be detained in the path of the teeth 19 so as to register five. After registering has taken place, the idler 22 is returned to its normal position by the engagement of the projection 30 with the inclined end 32 of the cam slot 31, and consequently the machine will be in position for repeated operation. After 60 the register has been operated, the arm 46 comes in contact with the inner face of the 65 bell crank lever 44 and forces the said lever

back into its normal position. The action causes its shoulder 49 to force the coin 50 between the fixed stop 41 and the spring stop 40 so that the coin will be discharged with considerable force against the inclined 70 face 42 of the block 38, and consequently the coins will be prevented from piling up below the mechanism. The wheels 16 can be turned by handle 14 only once around to register each coin, being stopped at the initial position by lever 46 after a complete 75 rotation.

Having fully described my invention, what I claim as new and desire to secure by Letters Patent of the United States is:

1. In a coin controlled mechanism, the combination with an operating shaft, of a toothed member operated from said shaft, a register, a laterally movable gear between said member and register, said toothed 85 member being provided with a cam for releasing said gear, and a coin actuated stop for limiting the movement of said gear.

2. In a coin controlled mechanism, the combination with an operating shaft, of a toothed member operated from said shaft, a register, a laterally movable gear between said toothed member and register, said toothed member being provided with a cam for returning said gear to normal position, 90 and a coin actuated member for controlling the movement of said gear.

3. In a coin controlled mechanism, the combination with an operating shaft of a toothed member operated from said shaft, a register, a laterally movable gear between said toothed member and register, said toothed member being provided with a cam for releasing said gear and returning same to normal position, and a coin actuated stop 100 for limiting the movement of said gear.

4. In a coin controlled mechanism, the combination with an operating shaft, of a gear mounted on said shaft and provided with the plurality sets of teeth, a register 110 having its shaft parallel with said operating shaft, a gear mounted on said register shaft, a laterally movable gear for connecting the second named gear with one of the sets of teeth on said first named gear, and a coin 115 controlled member for controlling the rotation of said operating shaft, said member also limiting the movement of said connecting gear.

5. In a coin controlled mechanism the 120 combination with an operating shaft, of a gear mounted on said shaft and provided with a plurality of sets of teeth, a register having its shaft parallel with said operating shaft, a gear mounted on said shaft, a 125 laterally movable gear for connecting said second named gear with one of the sets of teeth, and a coin controlled member for controlling the rotation of said operating shaft, said member also limiting movement of said 130

connecting gear, said first named gear being provided with a cam for returning said connecting gear to normal position.

6. In a coin controlled mechanism, the combination with an operating shaft, of a register actuated from said shaft, a coin actuated lever, and a pair of stops, one of said stops being spring actuated, said lever being adapted to force the coin between said

10 stops on its return to normal position.

7. In a coin controlled mechanism, the

combination with an operating shaft, of a register, movable connections between said shaft and register, a coin actuated lever for controlling said connections, and a pair of 15 stops for the coin, one of said stops being spring actuated, said lever being adapted to force the coin out between said stops on its return to normal position.

In testimony whereof, I have hereunto set 20 my hand and affixed my seal.

GILBERT L. HUFF. [L. s.]
